UNITED STATES PATENT OFFICE.

JOHN ROSE, OF PHILADELPHIA, PENNSYLVANIA, ASSIGNOR TO THE JOHN ROSE COMPANY, OF CAMDEN, NEW JERSEY.

RETAINING-BAND FOR UMBRELLAS.

SPECIFICATION forming part of Letters Patent No. 663,044, dated December 4, 1900.

Application filed August 4, 1899. Serial No. 726,087. (No model.)

To all whom it may concern:

Be it known that I, JOHN ROSE, a citizen of the United States, residing at Philadelphia, in the county of Philadelphia and State of Pennsylvania, have invented certain new and useful Improvements in Retaining-Bands for Umbrellas; and I do hereby declare the following to be a full, clear, and exact description of the invention, such as will enable others skilled in the art to which it appertains to make and use the same.

This invention relates to retaining-bands for umbrellas and parasols by which the ribs and cover are retained in compact form when the cover is wrapped around the ribs.

Articles of the kind mentioned have heretofore been made either of elastic material or of non-elastic material provided with means fixed to the bands whereby the loose ends are attached to the ends which are fastened to the cover. The objection to the first-mentioned kind is that the material of the band loses its elasticity in a short time and the band lengthens and becomes incapable of closely confining the ribs and cover. When a band of non-elastic material having fastening devices permanently secured at opposite ends is employed, there is considerable labor involved in changing the length of the bands to adapt them to umbrellas or parasols of different thicknesses when the articles are rolled, each size of umbrella requiring a special length of band.

The object of the present invention is to provide a retaining-band for umbrellas and parasols which shall be simple and cheap in construction, capable of being quickly and easily applied by an unskilled person, and which shall be capable of being adjusted to closely confine and retain the cover and ribs of an umbrella or parasol of any thickness when rolled.

With this object in view the invention consists of a retaining-band for umbrellas and the like having one part of the fastening device of a novel form and movable on the band and having the other part of the fastening device permanently secured to the band, whereby the band is rendered capable of use on umbrellas, &c., of varying thicknesses, substantially as hereinafter described and claimed.

The invention is illustrated in the accompanying drawings, in which—

Figure 1 is a side view of a rolled umbrella, showing the retaining-band in position to confine the cover and ribs. Fig. 2 is an edge view of the retaining-band. Fig. 3 is a sectional view of the movable portion. Fig. 4 is a view showing the outer face of the movable portion of the fastening device. Fig. 5 is a view showing the inner face thereof; and Fig. 6 is a sectional view of the same, the section being taken at right angles to that shown in Fig. 3.

In the drawings, A represents a band, of silk or other fabric, which is preferably inelastic and of approximately the length necessary to extend around the ribs and cover of an ordinary umbrella or parasol when the cover is wrapped closely around the ribs. One end of the band is preferably, though not necessarily, secured to the cover, leaving the other end free.

The fastening device by which the free end is secured to that attached to the cover may be of any suitable form, the principal requisite being that the parts be capable of quick connection and disconnection and that when connected they remain so during handling, shipping, &c. One form of fastening device which I employ is shown in the drawings. This consists of the headed projection B, secured to the band A at or near the point of attachment of the band to the cover, and the spring-socket C, formed in a plate c. The plate c, which is preferably of spring metal, is made, as shown, with its outer face convex in general contour, while its inner face is correspondingly concave. The plate has a slot C' therein near each side, forming bars C², which constitute the respective side edges of the plate. The plate is depressed in its outer face, and this depression forms the projection C³ on the inner face of the plate. The projection has in it the opening C⁴ of a size to receive the headed projection B, the opening being in its normal condition somewhat smaller in diameter than the diameter of the head. In order to allow the metal of the plate to be displaced to permit the entrance of the head of the projection, slits C⁵, radiating from the opening C⁴, are formed in the metal of the plate. In this way a spring-socket, into which

the headed pin may be introduced or from which it may be withdrawn by the exercise of a small amount of force applied in the right direction, is produced.

5. While I have particularly described the projection as being attached to the end of the band and the socket as being on the plate, it will be clear that the positions of the parts may, if desired, be reversed without departing from the spirit of the invention.

In attaching the plate to the band the free end of the latter is passed through one of the slots in the edge of the plate from the inner side of the plate, thence over the convex outer face of the plate, and then through the other slot. When the band is drawn taut, after being arranged as described, movement of the plate on the band when ordinary strain is placed on the plate is impossible. The 20 plate may readily be moved longitudinally of the band to shorten or lengthen the distance between the parts of the fastening to adapt the band to umbrellas or the like of different sizes by drawing up the band between the 25 slots in the plate and moving the plate in the direction required to effect the desired adjustment. When the band is drawn in position, as described, for use and the headed pin is in the socket, the portion *c* and the pin are 30 covered by the band, exposing only the edge of the plate *c*, as shown in the drawings, and thus giving the appearance of a buckle.

From the foregoing it will be clear that a retaining-band made as described is free of the disadvantages of articles of the kind as heretofore made and that their use will accomplish a great saving in time of operatives in attaching them, for the reason that they require no fitting, each band being capable 40 of application to an umbrella or parasol of any thickness.

Having thus described my invention, what I claim as new, and desire to secure by Letters Patent, is—

45 1. A retaining-band for umbrellas comprising a fabric band, a headed pin permanently attached to the band, and a plate having a concave outer face, with slots for the reception of the band on opposite sides thereof, the

plate having a convex inner face with an opening therein for the reception of the headed pin, substantially as described.

2. A fastening-band for umbrellas comprising a fabric band, a headed pin permanently attached to the band, a plate having a concave outer face, and slots near its edges for the reception of the band, the plate having a convex inner face, an opening in the convex portion for the reception of the headed pin, and slits extending radially from the opening, 55 the band being passed from the inside through one slot over the outer face of the plate, and thence inward through the other slot, substantially as described.

3. In a fastening device, the combination 65 of a ball member of a ball-and-socket fastener, and a socket member formed with a central concavo-convex portion with a central opening and having integral extensions and transverse openings adapted to receive and 70 adjustably hold the belt or other article, substantially as and for the purpose set forth.

4. A retaining-band for umbrellas, comprising a fabric band, a headed pin secured to the band, and a plate formed with a concavo-convex central portion having a central opening 75 therein to receive the headed pin, said central portion being provided with radial slots, and oppositely-extended end portions having slots for the reception of the band, substantially as shown and described.

5. A fastening-band for umbrellas, comprising a fabric band, a headed pin secured to the band, a plate having a concavo-convex portion formed therein with a central opening to 85 receive the headed pin and having radial slots leading therefrom and formed with slots near its respective ends to receive the band, the band being passed from the inside through one end slot over the outer face of the plate 90 and thence inward through the other end slot, substantially as shown and described.

In testimony whereof I affix my signature in presence of two witnesses.

JOHN ROSE.
